(57) **CLAIM**

The ornamental design for a portable battery-powered lighted fishing buoy with anchor, as shown and described.

DESCRIPTION

FIG. 1 is a perspective view of a portable battery-powered lighted fishing buoy with anchor showing my new design; FIG. 2 is a front elevational view thereof; FIG. 3 is a rear elevational view thereof; FIG. 4 is a side elevational view, with the opposite side elevational view being a mirror image thereof; FIG. 5 is a top plan view thereof; and, FIG. 6 is a bottom plan view thereof. The anchor line is shown broken away to indicate indeterminate length.
